UNITED STATES PATENT OFFICE.

ELMER S. HARRIS, OF HAVERHILL, MASSACHUSETTS, ASSIGNOR TO THE GOODYEAR SHOE MACHINERY COMPANY, OF PORTLAND, MAINE.

INSEAM-TRIMMING MACHINE.

SPECIFICATION forming part of Letters Patent No. 598,223, dated February 1, 1898.

Application filed May 22, 1896. Serial No. 592,528. (No model.)

To all whom it may concern:

Be it known that I, ELMER S. HARRIS, of Haverhill, in the county of Essex and State of Massachusetts, have invented certain new and useful Improvements in Inseam-Trimming Machines, of which the following is a specification.

The present invention relates to that class of machines for trimming off the surplus material of the welt, upper, and insole of a welted boot or shoe commonly known as an "inseam-trimming" machine.

The present invention has for its object to provide an improved means for progressively presenting to the work different portions of the cutting edge of the cutter, so that if one portion of the cutter becomes dull by contact with a tack or other substance a new portion is brought into operation.

The present invention has for its further object to provide a sharpening device to operate upon a portion of the cutter removed from the portion thereof then performing the cutting operation which is thereafter brought into position to make the cut.

To the above ends the present invention consists of the combination, with the cutter, of means for imparting thereto a to-and-fro motion in opposite directions to make the cut and a progressive movement in one direction to bring successive portions of its cutting edge into operative position.

The present invention further consists in the combination, with the cutter having the movements above described, of a grinder arranged to operate upon portions of the cutter not in operative position.

The present invention further consists of a new and useful combination of mechanical elements independent of their connection with the machine herein illustrated, as hereinafter described and claimed.

The accompanying drawings illustrate my invention as applied to the machine shown and described in Letters Patent of the United States No. 579,751, dated March 30, 1897, and in said drawings I have shown only so much of my complete machine as is necessary to illustrate the subject-matter of the claims herein.

In the accompanying drawings, Figure 1 represents a plan view of the mechanism embodying my improvements. Fig. 2 represents a side elevation of the same. Fig. 3 represents a section on line 3-3 of Fig. 1, the parts being somewhat enlarged. Fig. 4 represents an enlarged sectional detail on line 4-4 of Fig. 1. Fig. 5 represents a detail section on line 5-5 of Fig. 4. Fig. 6 represents an enlarged section on line 6-6 of Fig. 2, the grinding-wheel being omitted. Fig. 7 represents a detail elevation of a modified form of parts of the mechanism.

Similar reference characters indicate the same parts throughout the several views. 65

In the drawings, *a* represents a portion of the base or standard of the machine, and *a'* represents the arm of said standard which supports the operative parts of the mechanism embodied in my present invention. Secured to the side of the arm *a'* is a casting or bracket *a*², which is somewhat S-shaped in elevation, as shown in Fig. 3, said bracket being provided with bearings to permit both a rotary and longitudinal movement therein of a shaft *b*, a portion of which is threaded to form the worm *b'*. Fitted between two opposing surfaces of the bracket *a*² and surrounding the shaft *b* is a worm-wheel *b*², the hub of which is provided with two screws *b*³, having squared inner ends *b*⁴, (see Fig. 5,) which enter the longitudinal groove *b*⁵ in the shaft *b*. This construction permits of the shaft *b* being reciprocated while being gradually rotated by a worm *c*, engaging the worm-wheel *b*². The worm *c* is formed at one end of a shaft *c*', mounted in suitable bearings supported by the arm *a'* and having a belt-pulley *c*² at the other end. 75 80 85

d indicates the main driving-shaft of the machine, having a wrist-pin *d'*, which is connected by means of a pitman *d*² with a collar *d*³, secured to the end of the shaft *b*, whereby the said shaft *b* may be rapidly reciprocated while being slowly rotated by means of the worm *c* and worm-wheel *b*². 90 95

At the end of the arm *a'* of the frame and underneath the shaft *b* is a fork *a*³ of said arm, within which is a worm-wheel *e*, secured on a shaft *e*', mounted in bearings in said fork, 100

said shaft e' having at its outer end the wheel e^2 , around the periphery of which is secured the band of steel forming the cutter e^3 , the details of construction of said cutter-wheel 5 not forming a part, however, of the present invention. The worm-wheel e is engaged by the worm b' of the rotary and reciprocating shaft b , and therefore the cutter-wheel, while being given a rapid rotary oscillating motion 10 due to the rack-and-pinion operation of the worm b' and worm-wheel e , is gradually or progressively advanced or rotated by the slow worm-screw action of said worm and worm-wheel. Each rotary oscillating movement of 15 the cutter-wheel therefore slightly advances the position of any single point of the cutting-blade, so that new portions of said cutting-blade are being constantly brought into operative position to trim the work.

20 Secured to the arm a' is a bracket f , provided with bearings for the shaft of a grinding-wheel f' , which grinding-wheel may be raised or depressed, so as to be brought into engagement with or retracted from the per-

6

engagement with said cutter, substantially as described.

6. The combination with a cutter movable in a circular path, of means to impart to said cutter an oscillating movement to make the cut, and a progressive rotary movement to bring successive portions of its cutting edge into operative position, and a grinding device adapted to be brought into engagement with said cutter at a point removed from the

point of operation of the cutter, substantially as described.

In testimony whereof I have signed my name to this specification, in the presence of two subscribing witnesses, this 14th day of 15 May, A. D. 1896.

ELMER S. HARRIS.

Witnesses:

C. F. BROWN,
A. D. HARRISON.
